United States Patent Office

Des. 195,406
Patented June 11, 1963

195,406

INSTRUMENT PANEL

Roy E. Romine, 11485 Southland Road, Cincinnati, Ohio

Filed Mar. 20, 1962, Ser. No. 69,368

Term of patent 14 years

(Cl. D26—13)

FIG. 1 is a front elevational view of an instrument panel showing my new design.

FIG. 2 is a sectional view taken along the line 2—2 of FIG. 1.

FIG. 3 is a perspective view of the instrument panel shown in FIG. 1.

I claim:

The ornamental design for an instrument panel, as shown.
